UNITED STATES PATENT OFFICE.

CLAUDE R. DODGE, OF ST. GEORGE, UTAH.

TAG FORMER AND AFFIXER.

1,108,836.

Specification of Letters Patent. Patented Aug. 25, 1914.

Application filed August 19, 1913. Serial No. 785,554.

To all whom it may concern:

Be it known that I, CLAUDE R. DODGE, a citizen of the United States, residing at St. George, in the county of Washington 5 and State of Utah, have invented new and useful Improvements in Tag Formers and Affixers, of which the following is a specification.

The invention relates to a tag forming and 10 affixing machine, and more especially to machines of this character designed particularly for forming and affixing tags of the construction set forth and forming the subject-matter of my pending application, filed 15 August 23, 1912, bearing Serial Number 716,694.

The primary object of the invention is the provision of a machine wherein individual tags will be successively cut and formed 20 from a tag tape which is wound upon a reel and is fed in a novel manner to the tag forming and cutting mechanism of the machine, the tags after being formed and cut from the tape being readily and easily handled by the 25 operator of the machine so that they can be clamped firmly onto an article to be tagged during the continued operation of the machine.

Another object of the invention is the 30 provision of a machine of this character wherein the handling of the tag tape is accomplished in a unique manner, which tape consists of a metallic tape having a fabric covering and are provided with teeth so that 35 they can be used as the usual laundry tag and are joined together side by side in strip form which are wound upon a reel as a tape, the individual tags being bent into substantially U-shape and severed from the 40 tape to be subsequently clamped firmly upon the article to be tagged by the machine during a single operation thereof, the tags being in tape form greatly reduce the cost of the manufacture thereof and also enables 45 the formation of the individual tags successively while the machine is operating, and the easy and quick application or clamping thereof to the article to be tagged.

A further object of the invention is the 50 provision of a machine of this character in which the bending of each tag, the severing thereof from the tape, and the affixing of the tag to an article to be laundried is auto-

matically accomplished during the operation of the machine without requiring the stopping thereof at intervals and also avoiding the necessity of the hand bending and severing of the tags from the tape. 55

A still further object of the invention is to provide an automatic machine of the 60 class described which will embody the desired features of simplicity, durability and efficiency, and by means of which the tag may be formed, severed from the tape and affixed to the article to be laundried, rapidly, 65 conveniently and systematically.

Other objects will be in part obvious and in part pointed out hereinafter.

The invention accordingly consists in the features of construction, combination of elements and arrangement of parts which will be exemplified in the construction herein-after set forth, and the scope of the application of which will be indicated in the following claims. 70

In the drawings:—Figure 1 is an enlarged fragmentary side elevation of a machine constructed in accordance with the invention. Fig. 2 is a front elevation thereof. Fig. 3 is a top plan view. Fig. 4 is a vertical 80 longitudinal sectional view through the machine. Fig. 5 is a sectional view on the line 5—5 of Fig. 1. Fig. 6 is a sectional view on the line 6—6 of Fig. 1. Fig. 7 is a horizontal sectional view on the line 7—7 of 85 Fig. 1.

Similar reference characters indicate corresponding parts throughout the several views in the drawings.

Referring to the drawings by numerals, 90 the machine comprises a supporting table or stand 10 which may be of any desirable construction and on which is mounted a base or frame 11, preferably made from metal and is cast or otherwise formed. The base or frame 11 is fastened to the table or stand 10 by means of screws or bolts 12 as shown. At the front of the base or frame 11 is formed an anvil 13 which projects forwardly therefrom, and provided in the sides of the 95 said frame or base 11 are vertical alining guideways 14 in which slide the guide ribs 15 arranged opposite each other and projecting inwardly from a plunger presently described. 100

The plunger comprises spaced parallel

side bars 16 having integrally formed therewith the guide ribs 15, and are provided at their upper ends with a striker head 17, while spaced from the latter and formed 5 with the bars 16 is a hammer 18 which cooperates with the anvil 13 for the affixing of the tags on an article to be laundried in a manner presently described.

Mounted in the bars 16 of the plunger at 10 the lower end thereof is a cross pin 19 to which is connected a link 20, the same being designed for connection with any suitable foot treadle so that the plunger can be lowered when operating the foot treadle.

15 Formed on and depending from the table or stand 10 between the bars 16 of the plunger is an eye 21 to which is connected one end of a coiled retractile spring 22, the opposite end of which is connected to the cross pin 19, and this spring 22 serves to raise the plunger after it has been lowered by operating the foot treadle, (not shown).

Mounted in a seat or groove 23 formed in the top of the base or frame 11 is the depending tongue or wing 24 of a tag forming bar or rail 25 which projects outwardly forwardly of the frame or base 11 between the bars 16 of the plunger, the tag forming bar or rail 25 being provided in opposite side 30 faces with grooves or channels 26 which are designed for a purpose presently described.

Arranged within the frame or base 11 directly behind the rear end of the tag forming bar or rail 25 is a rotatable feed roller 35 27, the same being journaled upon an axle or spindle 28 mounted in the sides of the frame or base 11, the highest point of the outer periphery of the roller 27 being slightly elevated above the top of the base 40 or frame 11 and in plane level with the raised edge 29 of the tag forming bar or rail 25 so as to feed the tag tape 30 thereonto, which tape is normally wound upon a reel 31 journaled in supporting brackets 32 fixed 45 to the base or frame 11 at opposite sides thereof.

Formed on and rising above the top of the base or frame 11 are spaced bearings 32' in which is journaled an axle or spindle 33 having fixed thereto an intermittently movable feed roller 34 which is arranged directly above the roller 27 and co-acts therewith to positively feed the tape 30 from the reel 31 onto and directly over the tag forming bar 55 or rail 25 for the subsequent bending of each tag constituting the tape, in a manner presently described.

The roller 34 at one end is formed with a ratchet gear 35, while loosely journaled 60 upon the axle 33 is a cog wheel 36 carrying a pivoted spring-held pawl 37 which engages the teeth of the ratchet gear 35 for actuating the same to intermittently rotate the feed roller 34, the cog gear 36 being in meshing

engagement with the rack teeth 28 of a rack 65 plate 29 secured or otherwise fastened to one of the bars 16 of the plunger. It will be noted that on the lowering of the plunger the teeth 38 of the rack plate 29 will act upon the cog wheel 36, turning it in a direction which causes the spring-held pawl 37 to ride over a single tooth of the ratchet gear 35 so that on the raising of the plunger which causes the turning of the cog wheel 36 in the reverse direction the pawl 37 will lock 75 the ratchet gear 35 therewith, thereby turning the feed roller 34 a predetermined distance for the feeding of the tape 31 onto the tag forming bar or rail 25 the required distance for positioning a single tag 40 directly 80 over the raised edge 29 of the said bar or rail 25, whereby the tag 40 will be bent into substantially U-shape in a manner presently described.

Fixed to the base or frame 11 and overhanging the raised portion 29 of the tag forming bar or rail 25 is a guide arm 41 which holds the tag 40 in position with respect to the bar or rail 25 for the subsequent bending thereof into substantially U-shape 90 as will be hereinafter fully described.

Arranged rearwardly of the guide rollers 27 and 34 is a tag tape guide hood 42 which is fixed to the base or frame 11 and through which is trained the tag tape 30 to the feed 95 rollers 27 and 32, which co-act with each other for the feeding of the tape forwardly of the machine to bring the individual tags 40 successively in position to be bent into U-shape on the tag forming bar or rail 25 of 100 the machine.

The tag bending mechanism comprises a pair of spaced rollers 43 journaled upon stud spindles or axles 44 mounted in forked bearings 45 integrally formed with the side bars 16 of the plunger, the said rollers 44 being located contiguous to the striker head 17 of the said plunger and in alinement with the bars 16 of the plunger so that on the lowering of the latter the rollers 43 will engage 110 the straight tag 40 of the tape 30, and on the continued lowering of the plunger the tag 40 will be bent into U-shape about the tag forming bar or rail 25 as shown by dotted lines in Fig. 2 of the drawings. 115

Formed in the striker head 17 of the plunger is a dove-tail shaped groove 46 in which is fitted a correspondingly shaped combined abutment and severing block 47 which contacts with the bent tag 40 which has been advanced over the forming bar or rail 25 beyond the raised upper edge 29 thereof which forms a knife edge 48 at its outer end designed to coöperate with the inner cutting edge 50 of the block 47 to sever 125 the advanced tag 40 at its narrow connecting web 51 with the adjacent tag of the tape 30, the block 47 being held in the groove 46 by

means of a set screw 52 which is threaded in the head 17 of the plunger and works against the block, as shown.

Each tag 40 of the tape 30 is formed with 5 spurs 53 for the fastening thereof to an article after the tag 40 has been bent into substantially U-shape, the said spurs being accommodated in the grooves 26 in the sides of the tag forming bar or rail 25 so that the 10 spurs will not be flattened from their normal position when the tag is being bent into substantially U-shape.

The tag forming bar or plate 25 is of a proper width to form the U-shaped tag 15 when the latter is bent thereon on the lowering of the plunger and this bar or rail 25 is about the length of three tags 40 of the tape so that when the tape is fed through the rollers 27 and 32 one tag will be positioned directly over the raised portion 29 of the bar or rail 25, while the preceding tag next thereto will be located directly in the path of movement of the severing block 47 so that when the plunger is lowered the 20 said latter tag will be cut from the tape simultaneously with the bending of the succeeding tag next thereto and located over the raised portion 29 of the tag forming bar or rail 25, it being seen that the tag bent into 25 substantially U-shape will be severed from the tape 30 while the next tag adjacent thereto is being formed into substantially U-shape during the operation of the machine. After a single tag 40 has been severed from the tape 30 it is advanced to the outer end of the tag forming bar or rail 25 by the next tag adjacent thereto prior to the severing of the latter tag from the tape so that the severed tag can be readily 30 moved by the operator of the machine and conveniently mounted upon the article to be tagged. The said severed tag placed upon the article is first pressed over the edge of the said article with the fingers, 35 and then the article bearing the tag is positioned upon the anvil 13 so that the tag will lie thereon, whereby on lowering the plunger the hammer 23 will act upon the said tag for firmly clamping it upon the 40 article. During the clamping of the tag upon the article a new tag is bent into U-shape in the machine and the preceding tag which has been previously bent into U-shape is severed from the tape 30 on the 45 lowering of the plunger.

In the operation of the machine the tag tape is wound upon the reel 31 and its free end is trained over the guide hood 42 between the feed rollers 27 and 32 so that on 50 depressing the foot treadle the plunger is caused to lower and on the lifting of the plunger the first tag unsevered from the tape 30 is positioned directly over the raised portion 29 of the tag forming bar or rail 55 25, whereby on again lowering the plunger

the said tag will be bent into substantially U-shape so that on the return stroke of the plunger it will be positioned in the path of the severing block 47 which will cut the tag thus formed, when the said plunger is lowered, from the tape. Thereafter, the operator removes the tag which has been severed and presses it over the edge of an article to be laundried, with the fingers, and thereafter lays it on the anvil 13 to be 70 subsequently acted upon by the hammer 18 which firmly clamps the tag to the article in a manner as hereinbefore described. It will be apparent that throughout the continued operation of the machine the tags 75 will be formed into U-shape, subsequently severed from the tape 30, and thereafter firmly clamped to the article to be tagged.

From the foregoing it is thought that the construction and manner of operation 80 of the device will be clearly understood, and therefore a more extended explanation has been omitted.

What is claimed is:—

1. A tag forming and affixing machine 90 comprising a frame, superposed feed rollers journaled on the frame and between which is adapted to be fed a tag tape, a reciprocating plunger mounted on the frame, a hammer formed on the plunger, an anvil carried by the frame and projected below the hammer, a tag forming rail projecting outwardly from the frame into operative relation to the plunger, means for guiding such tape onto the tag forming rail, means 95 on the plunger for bending successively tags into U-shape from the tape about the said rail, and means carried by the plunger and acting upon the bent tags for singly severing the same from the tape. 100

2. A tag forming and affixing machine comprising a frame, superposed feed rollers journaled on the frame and between which is adapted to be fed a tag tape, a reciprocating plunger mounted on the frame, a hammer formed on the plunger, an anvil carried by the frame and projected below the hammer, a tag forming rail projecting outwardly from the frame into operative relation to the plunger, means for guiding such tape onto the tag forming rail, means 110 on the plunger for bending successively tags into U-shape from the tape about the said rail, means carried by the plunger and acting upon the bent tags for singly severing the same from the tape, and means on the plunger and acting upon one of the feed rollers for intermittently moving the same when the plunger is shifted in one direction. 115

3. A tag forming and affixing machine comprising a frame, superposed feed rollers journaled on the frame and between which is adapted to be fed a tag tape, a reciprocating plunger mounted on the frame, a 120

hammer formed on the plunger, an anvil carried by the frame and projected below the hammer, a tag forming rail projecting outwardly from the frame into operative relation to the plunger, means for guiding such tape onto the tag forming rail, means on the plunger for bending successively tags into U-shape from the tape about the said rail, means carried by the plunger and acting upon the bent tags for singly severing the same from the tape, means on the plunger and acting upon one of the feed rollers for intermittently moving the same when the plunger is shifted in one direction, and means for moving the plunger to normal position.

4. A tag forming and affixing machine comprising a frame, superposed feed rollers journaled on the frame and between which is adapted to be fed a tag tape, a reciprocating plunger mounted on the frame, a hammer formed on the plunger, an anvil carried by the frame and projected below the hammer, a tag forming rail projecting outwardly from the frame into operative relation to the plunger, means for guiding such tape onto the tag forming rail, means on the plunger for bending successively tags into U-shape from the tape about the said rail, means carried by the plunger and acting upon the bent tags for singly severing the same from the tape, means on the plunger and acting upon one of the feed rollers for intermittently moving the same when the plunger is shifted in one direction, means for moving the plunger to normal position, and means for guiding the tape between the feed rollers.

5. A tag forming and affixing machine comprising a frame, superposed feed rollers journaled on the frame and between which is adapted to be fed a tag tape, a reciprocating plunger mounted on the frame, a hammer formed on the plunger, an anvil carried by the frame and projected below the hammer, a tag forming rail projecting outwardly from the frame into operative relation to the plunger, means for guiding such tape onto the tag forming rail, means on the plunger for bending successively tags into U-shape from the tape about the said rail, means carried by the plunger and acting upon the bent tags for singly severing the same from the tape, means on the plunger and acting upon one of the feed rollers for intermittently moving the same when the plunger is shifted in one direction, means for moving the plunger to normal position, means for guiding the tape between the feed rollers, and tag bending means carried by the plunger and acting upon the tags of the tape to bend the same about the tag forming rails when the plunger is moved from normal position.

6. A tag forming and affixing machine 65 comprising a frame, a tag forming rail supported by the frame, a plunger reciprocatingly mounted upon the frame, means on the plunger and working at opposite sides of the rail for bending a tag into substantially 70 U-shape about said rail, means on the plunger and acting upon the tag to sever the same from a tag tape subsequent to the bending of the tag into U-shape, means on the plunger and on the frame for coöperation 75 with each other to clamp the severed tag to an article, and means for feeding the formed tag in the path of the clamping means.

7. A tag forming and affixing machine comprising a frame, a tag forming rail supported by the frame, a plunger reciprocatingly mounted upon the frame, means on the plunger and working at opposite sides of the rail for bending a tag into substantially 80 U-shape about said rail, means on the plunger and acting upon the tag to sever the same from a tag tape subsequent to the bending of the tag into U-shape, means on the plunger and on the frame for coöperation 85 with each other to clamp the severed tag to an article, means for feeding the formed tag into the path of the clamping means, and mechanism for feeding the tape into the path of the tag bending means and controlled by the plunger. 90

8. A tag forming and affixing machine comprising a frame, a tag forming rail supported by the frame, a plunger reciprocatingly mounted upon the frame, means on the plunger and working at opposite sides of 100 the rail for bending a tag into substantially U-shape about said rail, means on the plunger and acting upon the tag to sever the same from a tag tape subsequent to the bending of the tag into U-shape, means on the 105 plunger and on the frame for coöperation with each other to clamp the severed tag to an article, means for feeding the formed tag into the path of the clamping means, mechanism for feeding the tape into the path of 110 the tag bending means and controlled by the plunger, and means for holding the tape in proper position with respect to the tag bending means.

9. A tag forming and affixing machine 115 comprising a frame, a tag forming rail supported by the frame, a plunger reciprocatingly mounted upon the frame, means on the plunger and working at opposite sides of the rail for bending a tag into substantially 120 U-shape about said rail, means on the plunger and acting upon the tag to sever the same from a tag tape subsequent to the bending of the tag into U-shape, means on the plunger and on the frame for coöperation 125 with each other to clamp the severed tag to an article, means for feeding the formed tag into the path of the clamping means,

mechanism for feeding the tape into the path of the tag bending means and controlled by the plunger, means for holding the tape in proper position with respect to the tag bending means, and means for severing the bent tag from the tape and carried by the plunger.

In testimony whereof I affix my signature in presence of two witnesses.

CLAUDE R. DODGE.
